METHOD OF MOLDING DOUBLE-WALLED
HOLLOW CONCRETE BLOCKS

John M. Wilson, Glasgow, Scotland

Application December 28, 1949, Serial No. 135,379
In Great Britain February 4, 1948

6 Claims. (Cl. 25—155)

1

This invention relates to the moulding of double-walled hollow concrete blocks such as commonly used in the building trade.

The present invention comprises a method of moulding a double-walled hollow concrete block in which steam is introduced for a predetermined time directly into the mould into contact with the uncured block in order to speed up the curing of said block.

The invention is especially applicable to hollow concrete blocks comprising two spaced walls tied together by interconnecting ties. Preferably, such blocks are moulded with the spaced walls arranged horizontally above one another.

Preferably, a mould is adapted to make a number of blocks, arranged end to end, a dividing wall between the blocks having an opening to the hollow interior of the blocks so as to allow for the passage of the steam throughout the mould.

Preferably, a number of moulds are arranged side by side in a bank, a side member of one mould being common to the adjacent mould and having openings to the hollow interior of the blocks so as to allow for the passage of the steam throughout the bank of moulds.

The steam may advantageously be introduced to the mould simultaneously through a nozzle at each end, said nozzles being arranged directly opposite one another so that the two steam jets meet, thereby assisting in spreading the steam throughout the bank of moulds.

An embodiment of the invention will now be described, by way of example, with reference to the accompanying drawings whereon:

Fig. 1 is a section through a mould on the line 1—1 of Fig. 2 and Fig. 2 is a plan view of a bank of moulds.

Referring to the drawings, a bank of moulds comprises a series of individual moulds 10 arranged side by side so that a side member of each mould is common to the adjacent mould. The moulds in the present example are suitable for moulding hollow concrete blocks having two spaced walls 11 and 11a tied together by interconnecting ties 11b. These blocks are moulded with their spaced walls arranged horizontally, one above the other (as shown in Fig. 1 by chain dotted lines for clarity). In the present example each mould is adapted to accommodate four blocks, but this number may be varied as desired.

Each mould comprises side and end members. The end members 12 fit between the side members 13, being positioned by suitable stops (not

2

shown). The end members act as spacing pieces for keeping the sides of the mould at the exact distance apart. A bank of say forty-four moulds is thus assembled. The side members 13a at the extreme ends of the bank and certain intermediate side members (in the example, every eleventh side member) are provided with a dowel pin (not shown) at each end which fit into co-operating recesses in the base beams 14 on which the moulds rest. Said cooperating pins and apertures serve positively to position the side members and also the bank of moulds, as a whole, on said base beams.

The procedure in moulding the blocks is briefly as follows:

Each mould is fitted with three equi-spaced transverse division plates 15, which extend upwards from the bottom of the mould an amount giving the desired thickness of the "lower" spaced wall 11a of the block, these plates thus acting as dividing walls between the four blocks. The concrete is then poured into the mould and levelled off flush with said plates. An upper mould plate, comprising two half plates 16 having mating alternate projections and recesses of zig-zag shape as shown in Fig. 2, is then fitted in position in the mould. Said projections have cut-away portions 17 at their apices to allow for the interconnecting ties 11b to be placed in position. The upper mould plate is arranged parallel to the top and bottom of the mould and at a distance from the top equal to the desired thickness of the "upper" spaced wall 11. The interconnecting ties 11b are inserted through the cut-away portions 17, their lower ends being embedded in the concrete of the "lower" wall 11a and the upper ends extending above the upper plate 16. The upper transverse division plates 18 are then fitted in position and the concrete is poured into the spaces formed above said upper moulding plates and levelled off flush with the top of the mould.

When all the moulds in the bank are filled, steam is introduced into the mould. The end members of moulds spaced at regular intervals in the bank are provided with a connection 19 to which the steam supply is connected. The construction of the mould is such that the steam can pass throughout the entire length of the mould (as will be seen from Fig. 1) and also seeps through the zig-zag plates 16 to the upper wall 11 of the block. The side members 13 have openings 20 to the hollow portions of the blocks and thus the steam is free to pass throughout the bank of moulds. In the present example,

the bank of moulds has six steam connections on each side spaced at regular intervals and being connected to the steam supply by a flexible connection 21. It is advantageous to introduce the steam into the mould simultaneously at each end and to have the connections directly opposite one another so that the jets of steam meet and thereby the spreading of the steam through the bank of moulds is facilitated. The steam supply may be connected to each set of connections in turn or to any desired number simultaneously. For this purpose the connections 19 may incorporate a one way valve (not shown) or the free connections may be otherwise sealed off.

By introducing steam into the moulds, the curing of the concrete blocks is considerably accelerated. As a result of this it is possible to manufacture more blocks in a given number of moulds in a given time. Thus the cost of the steam which is relatively small is more than compensated by the time of curing, so that the same moulds can be used two or maybe three times more than if no steam was used, and hence a smaller factory and a smaller outlay on moulds and other equipment is required.

The steam is supplied from the boiler at about 60-100 lbs. per square inch but passes through a reducing valve. In practice it has been found that blocks should, on an average, be heated to 70 or 80 degrees centigrade. This heat is maintained for about 20 minutes and as a result there is a considerable reduction in time of curing.

The duration of heating of course varies appreciably in respect of the required time of curing and it also depends on the surrounding temperature in the atmosphere, the lower the surrounding temperature the longer the heating required.

As a result of this invention the time required to leave the concrete block to set in the mould is greatly reduced, for example, concrete which would normally take twenty-four hours to set will set in six hours with half an hour's steaming. These times will depend on various factors (for example type of mixture, climatic conditions, temperature of steam), but the ratio will always be substantially in the same proportions.

This particular invention is especially applicable to the double-walled blocks as the heating is applied to the interior surface and the conduction of the heat is from the inside out, thus ensuring effective action on the whole block. It has been proposed before to put blocks in steam chambers yet while this would economise in steam, it involves a lot of handling and the heat would be applied from the exterior of the block inwards and without, effective heat circulation there may be unequal temperature and curing.

In practice it is found beneficial to spray the "upper" spaced wall of the block to keep it moist, as it will be appreciated that the condensate will fall on the "lower" spaced wall and the "upper" spaced wall would be inclined to dry out.

I claim:

1. A method of moulding double-walled hollow concrete blocks with ties between the opposite walls thereof comprising pouring green concrete into the bottom of a mould to form one wall of the blocks, inserting in an upper part of the mould at least one pair of co-operating mould plates having opposed mating projections and recesses alternating and cut-out parts on their mating edges adapted to define locations for ties, inserting ties in said locations, pouring green con-

crete into the upper part of the mould on said mating plates to form the other wall of the blocks spaced above the first wall and bound thereto by the ties, introducing steam into the mould in the region between the two walls whereby it first makes contact with the inner surfaces of said walls and speeds up the hardening of the concrete, and then supplying moisture to the upper surfaces of the upper walls of the blocks to keep them moist during the steam treatment.

2. A method of moulding double-walled hollow concrete blocks with ties between the opposite walls thereof comprising pouring green concrete into the bottom of a mould to form one wall of the blocks, inserting in an upper part of the mould at least one pair of co-operating mould plates having opposed mating projections and recesses alternating and cut-out parts on their mating edges adapted to define locations for ties, inserting ties in said locations, pouring green concrete into the upper part of the mould on said mating plates to form the other wall of the blocks spaced above the first wall and bound thereto by the ties, introducing steam in jets into the mould in the region between the two walls from opposed sides of the mould whereby the steam jets meet and the steam spreads throughout the region between the inner surfaces of the two walls and first makes contact with the inner surfaces of the wall to speed up the hardening of the concrete, and then supplying moisture to the upper surfaces of the upper walls of the blocks to keep them moist during the steam treatment.

3. A method of moulding double-walled hollow concrete blocks with ties between the opposite walls thereof comprising pouring green concrete into the bottom of a mould to form one wall of the blocks, inserting in an upper part of the mould at least one pair of co-operating mould plates having opposed mating projections and recesses of zig-zag formation alternating and cut-out parts at the apices of the projections adapted to define locations for ties, inserting ties in said locations, pouring green concrete into the upper part of the mould on said mating plates to form the other wall of the blocks spaced above the first wall and bound thereto by the ties, and introducing steam into the mould in the region between the two walls whereby it first makes contact with the inner surfaces of said walls and speeds up the hardening of the concrete, and then supplying moisture to the upper surfaces of the upper walls of the blocks to keep them moist during the steam treatment.

4. A method of moulding double-walled hollow concrete blocks with ties between the opposite walls thereof comprising pouring green concrete into the bottom of a mould to form one wall of the blocks, inserting in an upper part of the mould at least one pair of co-operating mould plates having opposed mating projections and recesses of zig-zag formation alternating and cut-out parts at the apices of the projections adapted to define locations for ties, inserting ties in said locations, pouring green concrete into the upper part of the mould on said mating plates to form the other wall of the blocks spaced above the first wall and bound thereto by the ties, introducing steam in jets into the mould in the region between the two walls from opposed sides of the mould whereby the steam jets meet and the steam spreads throughout the region between the inner surfaces of the two walls and first makes contact with the inner surfaces of the walls to speed up hardening of the con-

crete, and then spraying moisture on to the upper surfaces of the upper walls of the blocks to keep them moist during the steam treatment.

5. A method of moulding double-walled hollow concrete blocks with ties between the opposite walls thereof in a multiple mould wherein the blocks are moulded with the spaced walls arranged horizontally above one another and wherein adjacent faces of adjacent blocks are separated by dividing members common to adjacent moulds, comprising providing openings in the dividing members in the parts thereof between the inter-wall spaces to provide inter-communication between said spaces throughout the entire multiple mould and providing nozzles at spaced locations along the sides of the multiple mould in the region of the inter-wall spaces, and, after the concrete has been poured to form the blocks, introducing steam into the mould through said nozzles whereby it spreads throughout the entire mould and provides conduction of heat from the inside outwardly to speed up

the hardening of all of the blocks in the multiple mould.

6. A method of moulding double-walled hollow concrete blocks as claimed in claim 5, in which the nozzles at each side of the multiple mould are directly opposed to the nozzles at the opposite side of the multiple mould.
